UNITED STATES PATENT OFFICE.

ERNEST DE WITT R. GARDEN, OF TARRYTOWN, NEW YORK.

ARTIFICIAL DENTURE.

No. 834,515.

Specification of Letters Patent.

Patented Oct. 30, 1906.

Application filed April 5, 1906. Serial No. 310,113.

To all whom it may concern:

Be it known that I, ERNEST DE WITT R. GARDEN, a citizen of the United States, residing at Tarrytown, in the county of Westchester and State of New York, have invented certain new and useful Improvements in Artificial Dentures; and I do declare the following to be a full, clear, and exact description of the invention, such as will enable others skilled in the art to which it appertains to make and use the same.

My invention relates to improvements in artificial dentures, and more particularly to bridgework; and it consists in certain novel features of construction, combination, and arrangement of parts hereinafter described and claimed.

The object of the invention is to provide a simple, practical, and efficient means for securing porcelain biting-surfaces or facings in their metal backings or holders for bridgework and the like.

The above and other objects, which will appear as the nature of my invention is better understood, are accomplished by means of the construction illustrated in the accompanying drawings, in which—

Figure 1 is a perspective view of an embodiment of my invention, showing a group of bicuspids and molars. Fig. 2 is a longitudinal view through the same. Fig. 3 is a transverse sectional view, and Fig. 4 is a perspective view, of one of the porcelain biting surfaces or facings.

Referring to the drawings by numeral, 1 denotes my improved artificial denture or bridge consisting of two bicuspids 2 3 and two molars 4 5, arranged in consecutive order, the outer bicuspid 2 and molar 4 being in the form of the usual crown to fit over natural teeth or the stumps thereof. These crowns 2 4 are connected by a metal bridge 6, which forms backings or caps 7 8 for the inner bicuspid 3 and the inner molar 4, said bicuspid and molar 3 4 having outer porcelain biting-surfaces or facings 9 10. These porcelain facings are formed in their inner ends with cavities 11 and in their inner faces with grooves or notches 12 to receive the cement which secures them in their metal caps or holders 7 8. The latter have their surrounding edges bent inwardly to a slight extent, as shown, and in their central portions are soldered or otherwise secured metal loops 13, which are adapted to fit into the cavities or recesses 11 in the facings 9 10, so that the cement 14, which fills the space around them and between the porcelain facings and the metal backings or caps, will bind said parts firmly together. It will be understood that this fastening means may be employed for securing the facings or biting-surfaces of any kind and number of teeth in their metal backings both in bridgework and other artificial dentures.

From the foregoing description, taken in connection with the accompanying drawings, the construction and operation of the invention will be readily understood without requiring a more extended explanation.

Having thus described my invention, what I claim as new, and desire to secure by Letters Patent, is—

The herein-described artificial dentures comprising crowns, a bridge connecting them and having a flanged edge and an anchor-loop, a facing on the bridge engaged by the flanged edge thereof, having a cavity to receive the anchor-loop and also having a recess on its inner side, and cement in said cavity and recess securing the facing to the loop and to the bridge.

In testimony whereof I have hereunto set my hand in presence of two subscribing witnesses.

ERNEST DE WITT R. GARDEN.
